GEORGE B. CROUSE, OF WOODCLIFF, NEW JERSEY, ASSIGNOR, BY MESNE ASSIGNMENTS,
TO NATIONAL CARBON COMPANY, INC., OF NEW YORK, N. Y., A CORPORATION OF
NEW YORK

ELECTRIC CONVERTER

Application filed January 6, 1927. Serial No. 159,454.

This invention relates to electric converters and more particularly to apparatus adapted to convert current derived from the ordinary house lighting circuits into current suitable for the operation of audion amplifier circuits.

The presence of alternating components in the current supplied from direct current lighting circuits or obtained by rectification from alternating current lighting circuits results in disturbances when such currents are supplied to the circuits of the usual audion amplifiers or radio receivers. Commutator ripples may be eliminated from a direct current supply circuit by means of filters, and smooth direct current may be obtained from an alternating current supply by means of rectifier and filter combinations. The problem of utilizing a house lighting circuit as a source of supply for energizing audion circuits has not been solved, however, by the construction of apparatus capable of converting current from the power line into smooth direct current since other difficulties arise when such apparatus is employed with an amplifier such as a radio receiver.

Proposed devices capable of delivering smooth direct current to a radio receiver have failed to operate satisfactory for many reasons, and principally for one or more of the following reasons: variations in lighting circuit voltage caused troublesome variations in the voltage supplied to the receiver; variations in the load caused wide variations in the output voltage of the converter-filter apparatus; the character of the impedances introduced into the plate circuits of the audions by the filter mesh resulted in interstage coupling and consequent distortion or instability in the receiver; no satisfactory means was provided for obtaining a bias voltage for the grids of audio amplifiers; and the condensers and the insulation of other elements of the filter mesh were liable to damage from surges set up when the converter-filter circuits were opened and closed.

An object of the invention is to provide apparatus operable from a source of alternating current, or of current containing alternating components, which apparatus will not

be affected in its operation by the nature of the load to which it supplies a smooth direct current and which is of such construction that it will not provide undesired couplings between portions of the load circuit which it supplies. A further object is to provide apparatus of the type stated which, when operated with radio receivers, will be free from the stated defects in prior devices. An object is to provide apparatus of the type stated and from which a grid bias potential may be derived without causing audio frequency distortion in a radio receiver. More specifically an object is to provide apparatus of the type stated in which a source of smooth direct current forms, in effect, a section of the filter network of the apparatus.

These and other objects of the invention will be apparent from the following description when taken with the accompanying drawing which comprises a circuit diagram illustrating one embodiment of the invention as associated with a typical radio receiver.

The apparatus as shown in the figure is designed for use with a source of alternating current and includes a transformer having a primary winding 1 which may be permanently connected to an alternating current lighting circuit by the terminals 2, 3. The transformer, which may be of the usual design, has an iron core 4, a secondary winding 5, and an additional secondary winding 6 for energizing the filament 7 of the rectifier 8. The rectifier may be of any desired construction but is illustrated as of the hot cathode high vacuum type, the plate 9 of the rectifier serving, with one side of the secondary winding 5, as the terminals of the rectified current line. The other terminal of the secondary 5 is connected to the midpoint of the filament winding 6 in the usual manner, and preferably a small capacity 10 is shunted across the secondary winding 5. The filter mesh is of conventional type and includes a series inductance 11 wound on an iron core 12 and arranged in the positive line between the two shunt capacities 13, 14.

The construction, so far as above described, is typical of known systems for obtaining rectified and filtered current from an alter-

nating current source. The respective junctions 15, 16 of the condenser 14 with the positive and negative leads of the filter mesh serve as terminals from which direct current 5 may be obtained. The voltage of the direct current and the degree of suppression of alternating components are dependent upon the design of the transformer, rectifier and filter elements. Apparatus of this type may 10 be readily constructed to deliver direct current of such voltage and such freedom from alternating components that the device may be used to energize the plate circuit of a single stage of audio frequency amplification. The usual practice for obtaining voltages of an order less than that existing between terminals 15, 16 has been to shunt a 15 tapped resistance or potentiometer across the terminals.

20 In accordance with this invention, an additional filter section is provided by elements which are serially connected to form a path in shunt across the output terminals of the known filter mesh.

25 As shown in the circuit diagram, the series elements of the added filter section comprise an impedance 17, a battery 18, and a resistance 19. The manner in which this 30 filter section modifies the operation of a customary converter-filter system or "battery-eliminator" may be best understood by first considering the plate current requirements of a typical radio receiver.

The typical radio receiver which is shown 35 in the diagram includes one stage of tuned radio frequency amplification, an audion detector, and two stages of audio frequency amplification. The input circuit of the audion R of the radio frequency stage comprises a 40 transformer having a primary 20 connected in the antenna circuit and a secondary 21 which is shunted by the tuning condenser 22. The radio frequency stage feeds into detector audion D through the radio frequency 45 transformer 23, and preferably a small condenser 24 connects the lower terminal of the transformer primary to the filament to complete the radio frequency circuit independent 50 of the plate power supply. Detector tube D feeds into the first audio amplifier A by means of an iron core audio frequency 55 transformer 25, a by-pass for radio frequency currents being provided by the condenser 26. The input circuit of the last 60 audio stage is provided by the secondary of the audio frequency transformer 27, the primary of the transformer being included in the plate circuit of the audion A. The audion PT of the last audio stage is of the 65 "power tube" type and the output circuit of the audion includes a loud speaker 28.

The filaments of the several tubes are supplied with current from a battery 29 and suitable resistances or ballast devices, not shown, 70 may be included in the filament circuits for

regulating the current supply to the several filaments. A feature of the invention comprises a simultaneous control of the filament and plate circuits. This is effected by including a relay or magnetic switch 30 in the 75 filament circuit of the rectifier tube 8 and connecting the winding 31 of the switch as a series element of the filament supply circuit of the receiver. A hand operated switch 32 controls the supply of current to the filament and, through the relay switch, simultaneously controls the operation of the plate current supply system.

For purposes of illustration, it may be assumed that the usual types of audions are 80 employed in the radio receiver. It is customary to obtain the desired grid bias for radio frequency amplifiers and audion detectors by connecting the grid returns of such stages to the appropriate filament terminal of the particular tube. The plate voltage of a radio frequency amplifier may be 90 volts while the plate voltage for a detector stage is usually 45 volts. Except for audio stages employing "power tubes", a plate voltage of 90 volts and 85 a grid bias of $4\frac{1}{2}$ volts is the usual practice. An amplifier stage employing a power tube, such as tube PT, operates satisfactorily with 90 130 volts on the plate when a negative bias of the order of 45 volts is applied to the grid. 95

Reverting now to the converter-filter system, the battery 18 which forms an element of the plate supply will preferably be of such design that the plate circuits of all tubes except power tube PT may be completed 100 through the battery. One side of the audion filament circuit is connected to the point $-B$ on the battery 18 and thus forms a common return for all of the plate circuits. Assuming that the several audions are of the 105 types operated under voltage conditions as stated above, the battery 18 will have a maximum positive potential, with respect to point $-B$, of the order of 90 volts. The lower sides of the primary windings of radio frequency 110 transformer 23 and audio frequency transformer 27 are connected to each other and to the +90 volt terminal of the battery 18. The primary of the first audio frequency transformer 25 is connected to an intermediate 115 point, +45, of the battery to apply 45 volts to the plate of detector audion D. The grid bias for audio amplifier A is obtained by connecting the grid return of that tube to the negative terminal, $-4\frac{1}{2}$, of the battery 18, 120 which terminal is so related to the point $-B$ that bias voltage of $4\frac{1}{2}$ is impressed upon the grid of audion A.

The plate potential for power tube PT is obtained directly from the positive line of the 125 converter-filter system and the grid return for that tube is connected directly to the negative line since the power tube has the maximum positive and negative potential requirements of the radio receiver. On the 130

drawing, the legends "+180" and "-45", as applied to the positive and negative lines, respectively, indicate voltages with respect to the point -B which may be used with the present commercial types of power tubes. It is to be understood that the invention is in no way limited to the particular voltages which have been recited as illustrative of the requirements of a common type of radio set. The invention of course contemplates that the converter will be designed to deliver voltages of the orders determined by the needs of the radio set or other equipment with which the apparatus is to be employed.

In any particular installation, the resistances of the impedance elements in series with the direct current source 18 are preferably so chosen that under the allowable variations of line voltage and/or of the value of the load, the direct current source 18 either floats on the line (neither taking up nor giving out energy) or charges or discharges by a small amount. The source of direct current is characterized by a low internal resistance, high capacity and a back electromotive force of considerable magnitude. Either dry or wet cells may be employed as the source of direct current, and in practice the ordinary dry batteries such as are now used as a plate current supply have been found to be well adapted for use as the direct current source 18.

Several important advantages are obtained when the direct current supply apparatus is constructed in accordance with the present invention.

Intermediate points in the shunt impedance path which is provided across the terminals 15, 16 by the series elements 17, 18 and 19 serve as terminals for obtaining the intermediate voltages customarily required in radio receivers. The shunt path also functions as an additional section of the filter mesh. It is well known that a degree of filtering satisfactory for the operation of the last stage of an amplifier will not ordinarily be sufficient for the operation of the earlier stages in a cascaded chain. In accordance with this invention only the last stage is energized directly from the output terminals 15, 16 of the filter mesh. The elements of the filter may be designed with reference to the requirements of the output stage as an additional filtering of current for supply to the earlier stages is effected by the auxiliary mesh to which those stages are connected. The impedance 17 will ordinarily be a pure resistance but may comprise a resistance and an inductive impedance in series when extreme filtering is required. The direct current source 18 cooperates with the impedance 17 to form the filter section and, from the viewpoint of filter operation, is the equivalent of a very large capacity. The resistance 19 also contributes to the filtering of the intermediate potentials and at the same time provides the

necessary potential drop to bias the grid of the last audio stage.

The action of the direct current source is not, however, limited to its operation as a capacitive element of a filter mesh. Due to its back electromotive force, coupled with a reasonably low internal resistance, the battery functions as a voltage stabilizer or regulator to prevent fluctuations of the voltage applied to input terminals 2, 3 from affecting any but the last stage of the receiver. Its low resistance and high capacity provide a short circuit for alternating current components set up in the last amplifier plate circuit and thus prevent such components from affecting the operation of other stages of the amplifier.

Although the presence of the battery 18 does not eliminate all fluctuations in potential between the points 15, 16 of the filter mesh, the effect of such voltage variations in the plate circuit of the last stage is offset by the fact that simultaneous variations take place across the resistance 19 and are thus applied in opposite phase to the grid of audion PT. In this way the grid bias is varied in exact relationship to the plate potential applied to the tube so that, within the limits of normal variations in power line voltage, the quality of the reproduction is not changed.

The element 18, due to its low internal resistance, has the additional function of acting as an electrical cushion to prevent abnormal voltages from being set up across the condensers 13, 14 of the filter mesh and bypass condensers 24, 26 of the radio set.

When the constants of the auxiliary filter mesh are so chosen that the battery is floating or substantially floating on the line, the effective life of a dry battery will be materially extended. In actual practice a dry battery in this position normally maintains itself in a condition of low internal resistance and high capacity. I conceive that the liberation of gases within the battery will cause a rise in resistance but that when the resistance reaches a certain value, the converter feeds energy into the battery and the gases are recombined, thus lowering the resistance and raising the capacity.

It is to be noted that the relay switch 30, 31 prevents the converter from feeding energy into the battery under conditions of no load.

It is to be understood that the specific constructions of the converter, filter and radio set in which the invention is incorporated or with which the invention may be associated are subject to wide variation. The character and the constants of the auxiliary impedance mesh may be adapted to meet particular requirements without departing from the spirit of the invention as set forth in the following claims.

I claim:

1. In apparatus for energizing the plate circuits of a plurality of audions from a source of direct current containing alternating components, a filter mesh comprising series and parallel impedance elements interposed between the said source and said plate circuits of audions, and an auxiliary source of smooth direct current potential connected across that portion of said mesh across which certain only of said plate circuits are connected.
2. In apparatus for energizing the plate circuits of a plurality of audions, a source of alternating current, a rectifier, a filter, and a source of pure direct current connected across the output of said filter, said direct current source having a voltage adequate for the supply of the plate circuits of certain only of said audions.
3. In apparatus for delivering space current to a plurality of audions whose voltage requirements are of different orders of magnitude, a source of rectified current, a filter mesh energized by said source and having output terminals at which the residual alternating components are suppressed to such degree that the space current for the audions of maximum voltage requirement may be obtained therefrom, and an auxiliary mesh connected across said filter output terminals and comprising, in series, an impedance connected to the positive terminal and a battery source of direct current, said battery source having terminals across which may be connected the plate circuits of audions whose voltage requirements are less than the maximum requirement.
4. Apparatus for supplying filtered direct current to the plate circuits of an audion amplifier of the type having stages whose voltage requirements are of different orders of magnitude, said apparatus comprising means energized from a light circuit and having output terminals delivering direct current of such voltage and sufficiently free from alternating components that the amplifier stage of maximum power requirements may be connected to said terminals, and a battery substantially floating between said terminals and of a voltage adequate for the supply of direct current to the plate circuit of another stage of said amplifier.
5. Apparatus for supplying direct current to an audion amplifier, said apparatus being of the type including a filter mesh having direct current output terminals across which an audion plate circuit may be connected, and an impedance path between said terminals affording means for delivering intermediate voltages for energizing the plate circuit of another audion, characterized by the fact that a portion of said impedance path comprises a source of direct current substantially floating between said terminals and of such voltage that said other plate circuit may be connected across the same.
6. An electrical converter circuit comprising in combination, a transformer having a primary adapted to be connected to a source of alternating current and a secondary proportioned to furnish space current potential; a rectifying device associated with said transformer secondary; a filter circuit connected to said transformer secondary and rectifying device; and an auxiliary mesh connected across the output terminals of said filter circuit and comprising, in series, an impedance connected to the positive output terminal of said filter, a battery source of space current, and a second impedance connected to the negative output terminal of said filter, said battery source having terminals across which may be connected the plate circuits of audions whose voltage requirements are less than the maximum requirement.
7. An electrical converter circuit adapted to be connected between an alternating current house-lighting circuit and a radio circuit including a plurality of vacuum tubes, comprising, in combination, a transformer having a primary adapted to be connected to said alternating current source and a secondary proportioned to furnish space current potential for said vacuum tube circuit, a rectifying device associated with said transformer secondary; a filter circuit connected to said transformer secondary and rectifying device; an auxiliary mesh connected across the output terminals of said filter circuit and comprising, in series, an impedance connected to the positive output terminal of said filter, a battery source of space current and a second impedance connected to the negative output terminal of said filter; means for connecting a negative point of said space current battery to the cathodes of said vacuum tubes; means for connecting a positive terminal of said space current battery to the anode of at least one of said vacuum tubes; means for connecting the positive output terminal of said filter to the anode of another of said vacuum tubes; and means for connecting the negative output terminal of said filter to the control electrode of said last-mentioned vacuum tube.
8. An electrical converter circuit adapted to be connected between an alternating current house-lighting circuit and a radio circuit including a plurality of vacuum tubes, comprising, in combination, a transformer having a primary adapted to be connected to said alternating current source and a secondary proportioned to furnish space current potential for said vacuum tube circuit; a rectifying device associated with said transformer secondary; a filter circuit connected to said transformer secondary and rectifying device; an auxiliary mesh connected across the output terminals of said filter circuit and

- comprising, in series, an impedance connected to the positive output terminal of said filter, a battery source of space current, and a second impedance connected to the negative output terminal of said filter; means 5 for connecting a negative point of said space current battery to the cathodes of said vacuum tubes; means for connecting a relatively more negative point of said battery to the control electrode of at least one of said vacuum tubes; means for connecting a relatively more positive point of said space current battery to the anode of at least one of said vacuum tubes; means for connecting the positive 10 output terminal of said filter to the anode of another of said vacuum tubes; and means for connecting the negative output terminal of said filter to the control electrode of said last mentioned vacuum tube.
- 20 9. An electrical circuit comprising, in combination, a house-lighting source of alternating current; a radio circuit including a radio frequency amplifier tube and an audio frequency amplifier tube; an electrical converter circuit interposed between said alternating current source and said radio circuit, said converter circuit including a transformer having a primary winding adapted to be connected to said alternating 25 current source and a secondary winding proportioned to furnish space current for said vacuum tubes, a rectifying device associated with said secondary winding, a filter circuit connected to said secondary winding and 30 said rectifying device, and an auxiliary mesh connected across the output terminals of said filter circuit, said mesh comprising, in series, an impedance, a space current battery, and a second impedance; a connection from a 35 negative point of said space current battery to the cathodes of said vacuum tubes; a connection from a positive point of said space current battery to the anode of said radio frequency amplifier tube; a connection from 40 the positive output terminal of said filter to the anode of said audio frequency amplifier tube; and a connection from the negative output terminal of said filter to a control element of said audio frequency amplifier tube.
- 45 10. An electrical circuit comprising, in combination, a house-lighting source of alternating current; a radio circuit including a radio frequency amplifier tube, a detector tube, and an audio frequency amplifier tube; an electrical converter circuit interposed between said alternating current source and said radio circuit, said converter circuit including a transformer having a primary winding adapted to be connected to said alternating 50 current source and a secondary winding proportioned to furnish space current for said vacuum tubes, a rectifying device associated with said secondary winding, a filter circuit connected to said secondary winding and said rectifying device, and an auxiliary mesh connected across the output terminals of said filter circuit, said mesh comprising, in series, an impedance, a space current battery, and a second impedance; a connection from a negative point of said space current battery to the cathodes of said vacuum tubes; a connection from a positive point of said space current battery to the anodes of said radio frequency amplifier tube and one of said audio frequency amplifier tubes; a connection from the positive output 55 terminal of said filter to the anode of said audio frequency power tube; and a connection from the negative output terminal of said filter to a control element of said power tube.
